UNITED STATES PATENT OFFICE.

WILLIAM D. CHASE, OF HACKENSACK, NEW JERSEY.

DESIGN FOR CHEWING-GUM.

SPECIFICATION forming part of Design No. 18,300, dated May 8, 1888.

Application filed March 22, 1888. Serial No. 262,183. Term of patent 3½ years.

To all whom it may concern:

Be it known that I, WILLIAM D. CHASE, of Hackensack, Bergen county, State of New Jersey, have invented and produced a new and original Design for Chewing-Gum, of which the following is a specification, reference being had to the accompanying drawings, forming part thereof.

Figure 1 is a front view of my newly-designed chewing-gum. Fig. 2 is a side view thereof; and Fig. 3, a section on line x z , Fig. 1.

The leading feature of my design consists of a ball or sphere having a partly rough surface and a partly smooth surface and embellished by curved lines.

a is a ball or sphere having a partly smooth surface and a partly rough or crimped surface, as shown at *b*. The ball or sphere *a* is embellished by curved lines *c*.

What I claim is—

The design for chewing-gum, consisting of a ball or sphere, *a*, having a partly rough or crimped surface, *b*, and a partly smooth surface, and curved lines *c*, substantially as shown.

WM. D. CHASE.
